(57) **CLAIM**

The ornamental design for a bag holder, as shown and described.

DESCRIPTION

FIG. 1 is a perspective view of a bag holder according to an embodiment of the claimed design;

FIG. 2 is a front view of the bag holder of FIG. 1;

FIG. 3 is a rear view of the bag holder of FIG. 1;

FIG. 4 is a left-side view of the bag holder of FIG. 1;

FIG. 5 is a right-side view of the bag holder of FIG. 1;

FIG. 6 is a top view of the bag holder of FIG. 1; and,

FIG. 7 is a bottom view of the bag holder of FIG. 1.

The features shown in broken lines represent portions of the bag holder which form no part of the claimed design.
